UNITED STATES PATENT OFFICE

THOMAS J. MURRAY, OF BEACON, NEW YORK

MACHINE FOR SHAPING CONICAL METAL FORMS

Application filed February 6, 1929. Serial No. 337,982.

The invention relates to machines for producing collars and base flanges on conical forms of metal, particularly in the manufacture of exhaust heads and similar forms.

5 The invention has for its object to provide a machine for the purpose stated, of a simple, compact and convenient structure whereby the bending or swaging of the metal may be readily accomplished with a minimum of effort.

Further, it is an object to provide a machine with die holders whose positions may be adjusted to permit use of dies of different sizes according to the particular size of article to 10 be formed.

Further, it is an object to provide a machine in which the flanging die is mounted so as to engage with the outer face of the conical form and serve to produce an outwardly projecting flange thereon which will lie in a plane 20 normal to the axis of the form.

Further, it is an object to provide a machine in which one of the collar forming dies will engage the outer face of the conical form 25 and the other collar forming die which cooperates with the same will operate within the form to produce a cylindrical collar on the blank, the axis of which collar will lie normal to the plane of the flange.

30 Further, it is an object to provide a screw device with nut members separately to operate the dies for forming the flange and collar.

Further, it is an object to provide a machine 35 wherein the flanging die will cooperate with the base and clamp the flange formed on the blank so as to hold the blank rigidly while the collar forming die is performing its functions.

Other objects will in part be obvious and in 40 part be pointed out hereinafter.

To the attainment of the aforesaid objects and ends, my invention consists in the novel details of construction and in the combination, connection and arrangement of parts 45 hereinafter more fully described and then pointed out in the claims.

In the accompanying drawings showing illustrative embodiments of the invention—

50 Figure 1 is a side elevation of a manually operated machine embodying the invention,

a blank being in position to be operated on;

Fig. 2 is a central vertical longitudinal section of the same;

Fig. 3 is a view similar to Fig. 2 with the flange formed on the blank;

Fig. 4 is a view similar to Figs. 2 and 3 but showing how a collar is formed;

Fig. 5 is a horizontal section on the line 5—5 of Fig. 3;

Fig. 6 is a central vertical longitudinal section of a modification of the invention; and

Fig. 7 is a detail section on the line 7—7 of Fig. 3.

In the accompanying drawings in which like numerals of reference designate like 65 parts in all of the figures, 10 designates a base which may be rectangular in form and made of metal. Centrally of the base is rigidly secured a vertical screw 11 on which is threaded a nut 12. The nut 12 is adapted to travel up 70 and down upon the screw in engagement with the threads thereof.

The nut 12 is provided with handles 13 whereby it may be rotated manually (see Fig. 1) or, if the machine is to be operated by 75 power, the nut (see 40, Fig. 6) may have gear teeth 41 to mesh with a suitable driving gear (not shown). If desired the handles 13 may be omitted and the nut used as a pulley to be 80 belt driven.

The nut 12 has a shoulder 14 which works in a recess 15 that is provided in the upper side of a head plate 16 through the central aperture of which the shank of the nut projects. In order to retain the plate 16 85 on the nut 12 the shank of the nut is threaded below the plate 16 and receives a nut 17 and a lock or jam nut 18. Thus when the nut 12 is turned on the screw it will tend to move the plate 16 up and down with it without rotating 90 the plate.

To the underside of the plate 16 is secured a plurality (preferably three or more) of arms 19, to the lower ends of which is rigidly fastened a die carrying ring 20 having an annular recess 21 in its upper face in which is disposed a removable die 22. The die 22 is held rigidly attached to the annular member 20 by a number of clamping devices 23.

As thus far described, it will be understood 100

that the plate 16, the member 20 and the die 22 carried thereby will move in unison.

In order positively to restrain the unit, composed of elements 16, 20 and 22, against turning around the axis of the screw, pins 39 may be secured to the base 10 and passed through holes in the ring 20 as indicated.

Between the member 20 and the plate 16 is disposed a nut 24 which is in threaded engagement with the screw 11. The nut 24 is provided at its upper portion with a pair of pivoted handles 25 that are normally maintained in a vertical position and are adapted to be swung downwardly to a horizontal position and serve as handles for adjusting the nut 24 upon the threaded shaft or screw 11.

Upon the outer face of the nut 24 is disposed an annular member 26, constituting a die carrier, which has a flange or shoulder 27 at its lower end to support an annular die 28. The die 28 does not require any special securing means for holding it in position upon the annular carrier 26. The carrier 26 and the die 28 are held loosely and swivelly in place upon the nut 24 by means of a nut 29 which is threaded onto the lower end of the nut 24.

30 designates an annular member (constituting an ordinary carrier) which is provided upon its inner side with a shoulder 32 and is supported by adjustable clamping members 31 which fit on the arms 19. Upon the recessed inner portion of the die carrier 30 is supported a die 33 which is rigidly clamped in position by a number of clamp members 34. As will be noted from Figure 2, when the upper die 33 is adjusted to contact the blank 35 at the place marked 36 it may serve to center and steady the blank during the flanging of the lower portion thereof, i.e., in moving from the position of Figure 2 to the position of Figure 3.

It will be understood that the purpose of the removable dies 22, 28 and 33 is to adapt the machine to the making of conical members of different diameters, and the purpose of making the clamping members 31 adjustable along the arms 19 is to adapt the machine to the making of conical members of different lengths.

In operation, a conical blank 35 is placed in position on the base 10 of the machine. Then the nut 12 and the assembled unit 16-18-19 etc. is placed on the screw 11 and the nut turned down to adjust the dies 22 and 33 to their proper positions in engagement with the blank 35 to form the proper angles at the places of contact 36 and 37 (it being understood that the distance between the dies 22 and 33 has previously been determined, and the clamps 31 secured tightly to the arms 19).

Further turning of the nut 12 downwardly will cause that portion of the blank 35 below the die 22 to be pressed downwardly and

outwardly until it lies in a plane normal to the axis of the blank (see Fig. 3) and be clamped tightly between the die 22 and the base 10.

The nut 24 is then rotated upwardly whereupon it will engage the blank 35 at the place marked 36 and upon further upward movement will force that portion of the blank which lies above the place 36 outwardly against the inner face of the die 33, thereby forming an annular collar whose axis lies normal to the plane containing the flange which has been formed at the bottom of the blank (see Fig. 4). This completes the formed article and it may then be removed by unscrewing the nut 12 from the screw 11, thereby removing the dies which work on the outer surface of the blank, and afterwards lifting the blank off over the screw.

When the arms 19 are inclined upwardly toward the screw, when it is desired to use the machine to make articles having a greater or lesser length than that shown, other die carriers 30 and clamps 31 are substituted. When, however, the arms are vertical, see Fig. 6, it is only necessary to raise and lower the clamps 31 along the arms to adjust the distance between the upper and lower dies as may be desired.

Having thus described my said invention, what I claim and desire to secure by Letters Patent is:

1. In a machine of the class described, a base, a pair of die carriers mounted above the base, ring dies on said carriers to engage the outer face of a conical blank adjacent its respective ends, means to move said carriers toward the base thereby to form an outwardly projecting flange at the base end of said blank, and a supplemental die carrier with a die over which the blank is located, and means to move said supplemental die to form a collar on the other end of said blank, substantially as shown and described.

2. In a machine of the class described, a base, a post extending upwardly from and mounted on said base, a head plate, means to mount said head plate on said post for vertical movement, a flanging die carried by said head plate and adapted to engage the outer face of a conical blank located around said post and on said base, means to force said die downwardly to press the lower portion of the blank into an annular flange lying in a plane normal to the axis of the blank.

3. In a machine of the class described, a base, a post extending upwardly from and mounted on said base, a head plate, means to mount said head plate on said post for vertical movement, a flanging die carried by said head plate and adapted to engage the outer face of a conical blank located around said post and on said base, means to force said die downwardly to press the lower portion of the blank into an annular flange lying in a

plane normal to the axis of the blank, and other means carried by said head plate and by said post for pressing the upper portion of the blank into a cylindrical collar.

is carried by and mounted swivelly on said lower nut and engages the blank on the inside, and means to turn said nuts.

4. In a machine of the class described, a base, a vertical screw secured to the base, a nut on the screw and means by which said nut may be turned, a head plate swivelly mounted on said nut, arms depending from said head plate, a flanging die for conical blanks carried by said arms, all being arranged whereby as said nut is screwed down said flanging die will press the lower portion of the conical blank located on the base into a flange lying in a plane parallel to the base and clamp same to the base.

9. In a machine of the class described, a base, a vertical screw carried by said base, an upper nut and a lower nut threaded on said screw, a head plate mounted on said upper nut, a base-flanging die suspended beneath and carried by said head plate to cooperate with said base in forming an outwardly projecting flange on a conical blank, a pair of collar-forming dies, one of which is carried by said head plate and engages the blank on the outside and the other of which is carried by said lower nut and engages the blank on the inside, and means to turn said nuts, said turning means for the lower nut including handles pivoted to said lower nut for the purposes specified. 70 75 80

5. In a machine of the class described, a base, a vertical screw secured to the base, a nut on the screw and means by which said nut may be turned, a head plate swivelly mounted on said nut, arms depending from said head plate, a flanging die for conical blanks carried by said arms, and means on said arms to engage the outer face of the conical blank near its upper end and steady same.

10. In apparatus of the class described, a 85

6. In a machine of the class described, a base, a vertical screw secured to the base, a nut on the screw and means by which said nut may be turned, a head plate swivelly mounted on said nut, arms depending from said head plate, a flanging die for conical blanks carried by said arms, means on said arms to engage the outer face of the conical blank near its upper end and steady same, said means comprising one of a pair of collar-forming dies, the other one of which being located on the screw at a place within the blank, and means to raise said other die to spread the upper portion of the blank and cooperate with the first die of the pair to form an annular collar on the blank.

base, a vertical screw secured to said base, an upper nut member threaded on said screw, a head plate swivelly mounted on said nut member, arms secured to said head plate and projecting toward said base, a die carrier secured to said arms at their lower extremities, a second die carrier secured to said arms at a given distance above the first die carrier, die rings mounted on said die carriers to engage the outer face of a conical blank near its upper and lower extremities respectively, means to turn said upper nut thereby to force said lower die toward said base and press a flange on the conical blank, substantially as described.

7. In a machine of the class described, a base, a vertical screw carried by said base, an upper nut and a lower nut threaded on said screw, a head plate mounted on said upper nut, a base-flanging die suspended beneath and carried by said head plate to cooperate with said base in forming an outwardly projecting flange on a conical blank, a pair of collar-forming dies, one of which is carried by said head plate and engages the blank on the outside and the other of which is carried by said lower nut and engages the blank on the inside, and means to turn said nuts.

11. In apparatus of the class described, a base, a vertical screw secured to said base, an upper nut member threaded on said screw, a head plate swivelly mounted on said nut member, arms secured to said head plate and projecting toward said base, a die carrier secured to said arms at their lower extremities, a second die carrier adjustably secured to said arms at a given distance above the first die carrier, die rings removably mounted on said die carriers to engage the outer face of a conical blank near its upper and lower extremities respectively, means to turn said upper nut thereby to force said lower die toward said base and press a flange on the conical blank, substantially as described. 105
110
115

55 8. In a machine of the class described, a base, a vertical screw carried by said base, an upper nut and a lower nut threaded on said screw, a head plate swivelly mounted on said upper nut, a base-flanging die suspended beneath and carried by said head plate to co-operate with said base in forming an outwardly projecting flange on a conical blank, a pair of collar-forming dies, one of which is carried by said head plate and engages the blank on the outside and the other of which

12. In apparatus of the class described, a base, a vertical screw secured to said base, an upper nut member threaded on said screw, a head plate swivelly mounted on said nut member, arms secured to said head plate and projecting toward said base, a die carrier secured to said arms at their lower extremities, a second die carrier secured to said arms at a given distance above the first die carrier, die rings mounted on said die carriers to engage the outer face of a conical blank near its upper and lower extremities respectively, means to turn said upper nut thereby to force said lower die toward said base and press a flange 125 130

on the conical blank, a lower nut member on said screw, a die carrier and die swivelly mounted on said lower nut member, and means to turn said lower nut member to cause said last-named die, in cooperation with the upper die member, to form a collar on the blank.

Signed at the city of New York, in the county of New York and State of New York,
10 this 21st day of January, one thousand nine hundred and twenty-nine.

THOMAS J. MURRAY.
